JACOB RUSH SNYDER, OF PITTSBURGH, PENNSYLVANIA.

STEAM-ENGINE REVERSING-GEAR.

1,187,020.

Specification of Letters Patent. Patented June 13, 1916.

Application filed July 23, 1915. Serial No. 41,501.

To all whom it may concern:

Be it known that I, JACOB RUSH SNYDER, a resident of Pittsburgh, in the county of Allegheny and State of Pennsylvania, have 5 invented a new and useful Improvement in Steam-Engine Reversing-Gear, of which the following is a specification.

This invention relates to mechanism for operating the reversing gear of steam engines, such as locomotives.

The object of the invention is to provide a fluid actuated device for moving the usual valve gear, and which is so arranged as to insure positive movement of the valve gear 15 without danger of any kick-back to the engineer or operator, and also one which will prevent the valve gear from being moved farther than intended.

The invention comprises the construction 20 and arrangement of parts hereinafter described and claimed.

In the accompanying drawings, Figure 1 is a vertical sectional view through the actuating cylinder and the locking device for 25 the reach rod, and showing the valve mechanism for the operating cylinder and its actuating means in elevation; Fig. 2 is a vertical section through the valve mechanism and its actuating means on the line 2—2, 30 Fig. 1; Fig. 3 is a horizontal section on the line 3—3, Fig. 1; Fig. 4 is a similar section on the line 4—4, Fig. 1; Fig. 5 is a horizontal section on the line 5—5, Fig. 1; Fig. 6 is a vertical section through the 35 reach rod locking device on the line 6—6, Fig. 1; Figs. 7, 8 and 9 are plan views respectively of the seat, the first or lower rotary disk, and the second or upper rotary disk of the valve mechanism; and Figs. 10, 40 11, 12, 13 and 14 are diagrammatic views showing the valve mechanism respectively in normal release position, in lock applying position, in cylinder application and lock applying position, and in cylinder application 45 and lock release position.

In the drawings, 1 represents a reversing cylinder in which works the piston 2 having its piston rod 3 connected to the reach rod 4 which is connected to the usual reversing link mechanism of the engine and which need not be shown. When the piston 2 is moved in one direction the link mechanism will be moved to, say, drive the engine forwardly, and when the piston 2 is moved 50 in the opposite direction the link mechanism will be moved to drive the engine back- 55

wardly. These movements of the piston are secured by admitting and exhausting fluid pressure alternately to and from the opposite ends of the cylinder. A locking device 60 is provided for preventing movement of the piston and the rods connected thereto until the actuating means has been fully moved to the desired position, in order to prevent the fluid pressure admitted to the cylinder 65 from moving the actuating lever and injuring the engineer. The locking mechanism shown is in the form of a clamp embracing the reach rod, and comprises a stationary member 5 having pivotally connected thereto as at 6 the gripping jaw 7, the latter being provided with an extension or arm 8 which is arranged to be actuated by a projection 9 on a piston 10 working in a suitable cylinder 11 and arranged to have 70 a suitable motive fluid introduced thereto on the opposite side of the piston 10 in order to drive the projection 9 against the arm 8 and cause the jaw 7 to grip the reach rod, as will be readily understood. 80

A special form of valve and actuating means therefor is provided for alternately admitting pressure to and exhausting it from the opposite ends of the cylinder 1 and also admitting motive fluid to and exhausting it from the cylinder 11 of the locking device. This valve mechanism and its actuating means comprises a stationary member 14 provided with a circular portion or hub 15 on which are rotatably mounted 90 a sector 16 and the valve actuating handle 17. The sector 16 is provided with a downwardly projecting arm 18 connected through link 19 and lever 20 to the reach rod 4, so that the movement of the reach rod by the 95 power cylinder 1 imparts movement to this sector.

Secured to the part 15 of the stationary member 14 is a valve which comprises a suitable casing 21 closed at its outer end by the 100 head 22 whose inner face forms the seat 23 for the valve. Working on said seat is the first or lower disk 24, whose upper or inner face in turn forms a seat for the top or second rotary disk 25. The two rotary disks 105 are held to the seat and against each other by means of a compression spring 26. The disk 24 is provided with a hollow stem which projects through the head 22 and has secured to its outer side an arm 28 secured to the actuating handle 17. The top 110 or inner rotary disk 25 is also provided with

a hollow stem which extends through the hollow stem of the disk 24 and has secured to its outer end a cross member 30, to each end of which is connected by a slot and pin 5 connection an arm or bracket 31 secured to a bar 32 which is slidably mounted on the handle 17, extending through guide loops 33 on said handle. The upper end of the handle is enlarged, and vertically movable therein is a handle-locking member or dog 35, which at its lower end is provided with a tooth 36 arranged to engage a notch 37 in the curved portion of sector 16. This dog also has a rearwardly projecting part 38 carrying one or more teeth arranged to engage with the teeth 39 on a curved rack portion of the stationary member 14. The locking dog 35 is normally held depressed by means of a spring 40 seated in a pocket in 20 said locking dog and having its upper end engaging a bearing member 41 resting against the cross bar 42 of the handle. Each of the vertically slidable bars 32 is provided at its upper end with an enlargement or finger grip 43, both of which engage underneath a flange 44 formed on the upper part of the locking dog 35.

The handle 17 is held against accidental or unintentional movement in either direction by means of a pair of locking plungers 45 mounted in bosses 46 carried by the sector 16 and normally held in projected position by springs 47. The forward or outer ends of these locking plungers are beveled, 30 as shown in Figs. 1 and 5, and each sliding bar 32 is provided with a projection 48 arranged when the bar is lifted to contact with the beveled end of the locking plunger and push it backwardly against the tension of the spring 47, and thus permit the handle 17 to be moved in the direction of whichever one of the two sliding bars has been lifted.

The valve casing 21 is provided with an inlet 50 for motive fluid to the space above 45 the rotary disks in said casing. The valve seat is provided with three ports, to-wit, port 51 connected by pipe 52 to one end of the cylinder 1, port 53 connected by pipe 54 to the opposite end of the cylinder 1, and port 55 connected by pipe 56 to port 57 of the lock actuating cylinder 11. The lower rotary disk 24 is provided with three ports, marked 58, 59 and 60 respectively, which extend entirely through the disk and which 50 communicate with long grooves on the lower face of the disk. The top disk 25 is provided with two circular ports, 61 and 62, and two elongated ports 63 and 64, extending entirely through the disk, and on its 55 lower face is provided with three arc-shaped grooves or cavities, 65, 66 and 67, each of which connects through a radial passage 68 in the valve body with the central opening or passage 69 through the stem of said valve, 60 and which latter passage forms the exhaust.

Normally the handle 17 is in the position shown in Fig. 1, being held between the locking projections 45 on each side thereof and with the locking dog 35 engaging both the notch 37 in the sector 16 and also engaging the rack bar 39 of the stationary member 14. In this position the piston 2 is midway of the length of the cylinder 1 and the valve mechanism is in the position shown in Fig. 10. The ports 58, 59 and 60 of the disk 24 register respectively with the ports 51, 53 and 55 of the valve seat, and the cavities 65, 66 and 67 of the upper disk register respectively with the ports 58, 59 and 60 of the disk 24, and therefore afford communication from both ends of the cylinder 1 and also from the lock actuating cylinder 11 to the atmosphere.

To shift the valve gear the operator lifts on the enlargement 43 of one of the sliding bars 32, thereby lifting said sliding bar. Assume that he lifts the left hand one of said bars, viewing Fig. 1. This through the bracket 31 imparts rotary movement to the cross head 30 on the outer end of the stem 85 of the inner disk 25 (the opposite one of the sliding bars 32 is free to move downwardly to permit such rotary movement). This movement is sufficient to rotate the top or innermost rotary disk clockwise to the position shown in Fig. 11, which brings the port 63 of said rotary disk over the port 58 in the lower disk, and as the latter still registers with port 51 in the valve seat this permits motive fluid to pass through pipe 52 to the outer end of cylinder 2. At the same time the port 62 in the top rotary disk registers with port 60 in the bottom rotary disk, and as this latter port still registers with port 55 in the valve seat motive fluid also passes to the cylinder 11 of the device for locking the reach rod. In passing to this position the port 63 is brought into register with port 58 before the port 62 is brought into register with port 60, but this is only for a very brief time, and inasmuch as the capacity of cylinder 1 is much greater than the capacity of the cylinder 11, the locking device is actuated before the piston 2 has opportunity to move. This locking device 90 grips the reach rod and prevents any back movement of the handle 17 through the links and levers 20, 19 and 18, until the locking device is released.

The upward movement of the sliding bar 32 lifts the locking dog 35 out of engagement with the sector 16 and out of engagement with the rack 39, and, also, the projection 48 pushes backwardly the locking plunger 45 on the left hand side of the handle. The operator can then move the handle 17 to the left, to any desired position. This movement of the handle 17 carries with it both of the disks 24 and 25 of the valve mechanism, say, to the position shown in 115 120 125 130

Fig. 12, but without disturbing the relations of the two disks 24 and 25 to each other, and inasmuch as the ports in the lowermost disks end in long arc-shaped grooves on the lower face of the disk, none of the connections described in the last previous position are disturbed.

As soon as the engineer has moved the handle 17 as far as desired, he releases the projection 43 on the sliding rod 32, and this allows the dog 35 to drop, but not to its full extent, because its lower end will strike against the upper surface of sector 16. The teeth on rack 39 are, however, deep enough so that they will nevertheless be engaged by the rearward projection 38 on the locking dog 35, sufficiently to lock the handle in that position. As soon as the engineer releases the projection 43 to allow the locking dog 35 to drop, the downward movement of the sliding rod 32 imparts rotary movement to the cross head 30, but in the opposite direction from that given to it when the sliding rod was raised, but not to the same extent, because the locking dog 35 cannot fall fully to its lowermost position. This brings the disks to the position shown in Fig. 13, in which the position of the lower disk 24 is not disturbed from the position shown in Fig. 12, but the top disk 25 has been rotated in the reverse direction sufficiently to take the port 62 out of register with port 60 in the bottom disk, and bring the cavity 67 of the top disk into register with the port 60 in the bottom disk, as a consequence of which the cylinder 11 exhausts through port 55 in the valve seat, port 60 in the bottom rotary disk and cavity 67 and passage 68 in the top disk, to the central exhaust port 69. The piston 2 is now free to move, and move the valve gear, but, it will be observed, that by this time the handle is mechanically locked by means of the projection 38 of the locking dog 35 engaging the rack 39.

Consequently, any back kick or sudden movement due to the sudden movement of the piston 2 cannot injure the engineer. As the piston 2 moves outwardly, by means of lever 20, link 19 and arm 18 the sector 16 is moved, until the notch 37 therein comes underneath the locking dog 35, when the toothed end 36 of said dog will drop down into such notch. The further downward movement of the locking dog permits the sliding rod 32 to move downwardly fully to its normal position, thereby further rotating the top disk 25 backwardly to its position normal to the lower disk 24. This position is shown in Fig. 14. In this position the relation of the lower disk of the valve seat described in the previous position is not disturbed, the long arc-shaped cavities in the lower face of said disk still registering with the ports 51, 53 and 55 in the valve seat. The top disk now is moved back so that not

only does cavity 67 still register with port 60 in the lower disk, but cavity 65 is also brought into register with the port 68 in the lower disk, as a consequence of which the cylinder 1 is also released. As a consequence, the movement of the piston 2 through the members 20, 19, 18 and 16 automatically brings about the release of pressure from the cylinder 1 as soon as the piston 2 has moved to the desired extent.

As the sector 16 is moved in the manner just described, the locking plunger 45 which had been retracted when the sliding bar 32 was lifted, slides along the back face of the handle 17, and when the sector has been brought to its final position said projection 45 is pushed outwardly by its spring 47.

When it is desired to drive the engine in the opposite direction from that described, the engineer lifts the projection 43 of the sliding bar 32 on the opposite side of the handle 17 from that just described, when he will be able to move the handle in that direction, and bring about exactly the same changes as just described, except that in this case the fluid pressure will be admitted through port 53 of the valve seat to the inner end of cylinder 1. The sector 16 is provided on its rear face with a notch or socket 70 for receiving a bar or lever for moving said sector in cases when it cannot be automatically moved by the cylinder 1, as occurs when the engine is second in a double header and therefore has no control over the compressed air in its system.

The valve mechanism described insures the movement of the valve gear positively and to the desired extent and requires no attention of the engineer other than to unlock the actuating handle 17 by lifting one of the sliding rods 32 and then moving the handle to the desired position, all of the other operations taking place entirely automatically. The mechanism is so arranged as to prevent the engineer from moving the handle except in the direction of the particular sliding rod 32 which he has lifted.

What I claim is:—

1. In valve reversing mechanism, the combination of a reversing cylinder, a piston therein, a reversing rod connected to said piston, a fluid pressure actuated locking device for said rod, and valve mechanism controlling the supply and exhaust of motive fluid to and from the two ends of said cylinder and to and from said locking device and arranged to admit motive fluid to the locking device to lock the reversing rod simultaneously with the admission of motive fluid to either end of said cylinder to actuate the reversing rod.

2. In valve reversing mechanism, the combination of a reversing cylinder, a piston therein, a reversing rod connected to said piston, a fluid pressure actuated locking de-

vice for said rod, and valve mechanism controlling the supply and exhaust of motive fluid to and from the two ends of said cylinder and to and from said locking device and arranged to admit motive fluid to the locking device to lock the reversing rod simultaneously with the admission of motive fluid to either end of said cylinder to actuate the reversing rod and to exhaust the motive fluid from said locking device upon the setting of said valve mechanism to the desired position.

3. In valve reversing mechanism, the combination of a reversing cylinder, a piston therein, a reversing rod connected to said piston, a fluid pressure actuated locking device for said rod, valve mechanism controlling the supply and exhaust of motive fluid to and from the two ends of said cylinder and to and from said locking device and arranged to admit motive fluid to the locking device to lock the reversing rod simultaneously with the admission of motive fluid to either end of said cylinder to actuate the reversing rod, and means actuated by the travel of said reversing rod for causing said valve mechanism to exhaust said cylinder when the piston has traveled the required distance.

30 4. In valve reversing mechanism, the combination of a reversing cylinder, a piston therein, a reversing rod connected to said piston, a fluid pressure actuated locking device for said rod, valve mechanism controlling the supply and exhaust of motive fluid to and from the two ends of said cylinder and to and from said locking device and arranged to admit motive fluid to the locking device to lock the reversing rod simultaneously with the admission of motive fluid to either end of said cylinder to actuate the reversing rod and to exhaust the locking device when said valve mechanism has been set to the desired position, and means actuated by the travel of said piston for causing the valve mechanism to exhaust said cylinder when the piston has traveled the required distance.

50 5. In valve reversing mechanism, the combination of a reversing cylinder, a piston therein, a reversing rod connected to said piston, a fluid pressure actuated locking device for said rod, valve mechanism controlling the supply and exhaust of motive fluid to and from the two ends of said cylinder and to and from said locking device, an actuating handle for said valve mechanism, a lock for said handle, means for releasing said handle lock arranged to simultaneously actuate said valve mechanism to admit motive fluid to said rod locking device to lock said rod and to said cylinder to actuate said rod, and means for permitting the partial restoration of said valve mechanism after the handle has been moved to thereby exhaust said rod locking device and release

said rod while maintaining the supply to said reversing cylinder.

6. In valve reversing mechanism, the combination of a reversing cylinder, a piston therein, a reversing rod connected to said piston, a fluid pressure actuating locking device for said rod, valve mechanism controlling the supply and exhaust of motive fluid to and from the two ends of said cylinder and to and from said locking device, an actuating handle for said valve mechanism, a lock for said handle, means for releasing said handle lock arranged to simultaneously actuate said valve mechanism to admit motive fluid to said rod locking device to lock said rod and to said cylinder to actuate said rod, means for permitting the partial restoration of said valve mechanism after the handle is moved to thereby exhaust said rod locking device and release said rod while maintaining the supply to said reversing cylinder, and means actuated by the travel of the piston for causing the valve mechanism to exhaust said cylinder when the piston has traveled the required distance. 90

7. In valve reversing mechanism, the combination of a reversing cylinder, a piston therein, a reversing rod connected to said piston, a fluid pressure locking device for said rod, valve mechanism controlling the supply and exhaust of motive fluid to and from the two ends of the cylinder and to and from said locking device, an actuating handle for said valve mechanism, a lock for said handle, and connections from said handle lock whereby upon the release thereof the valve mechanism is actuated to admit motive fluid to said rod locking device to lock said rod and to said cylinder to actuate said rod, and arranged when said handle locking means is released to partly actuate the valve mechanism to exhaust the locking device and release said rod while maintaining the supply to the reversing cylinder. 100

8. In valve reversing mechanism, the combination of a reversing cylinder, a piston therein, a reversing rod connected to said piston, a fluid pressure locking device for said rod, valve mechanism controlling the supply and exhaust of motive fluid to and from the two ends of the cylinder and to and from said locking device, an actuating handle for said valve mechanism, a lock for said handle, connections from said handle lock whereby upon the release thereof the valve mechanism is actuated to admit motive fluid to said rod locking device to lock said rod and to said cylinder to actuate said rod and arranged when said handle locking means is released to partly actuate the valve mechanism to exhaust the locking device to release said rod while maintaining the supply to the reversing cylinder, and means actuated by the travel of said piston for further actuating said valve mechanism to 110

exhaust said cylinder when the piston has traveled the required distance.

9. In valve reversing mechanism, the combination of a reversing cylinder, a piston therein, a reversing rod connected to said piston, a fluid actuated locking device for said rod, valve mechanism controlling the supply and exhaust of motive fluid to and from the two ends of said cylinder and to and from said rod locking device, an actuating handle for the valve mechanism, a lock for said actuating handle, means for releasing said handle lock and therewith actuating said valve mechanism to admit motive fluid to the rod locking device to lock said rod and to the cylinder to actuate said rod, and means for restoring said handle locking device after the handle has been moved and thereby partially restoring the valve mechanism to exhaust the rod locking device and release said rod.

10. In valve reversing mechanism, the combination of a reversing cylinder, a piston therein, a reversing rod connected to said piston, a fluid actuated locking device for said rod, valve mechanism controlling the supply and exhaust of motive fluid to and from the two ends of said cylinder and to and from said locking device, an actuating handle for the valve mechanism, a lock for said actuating handle, means for releasing said handle lock and therewith actuating said valve mechanism to admit motive fluid to the rod locking device to lock said rod and to the cylinder to actuate said rod, means for restoring said handle locking device after the handle has been moved and thereby partially restoring the valve mechanism to exhaust the rod locking device and release said rod, and means actuated by the travel of said piston and permitting the handle locking device to be fully restored when the piston has traveled the desired distance and thereby further actuate the valve mechanism to release the cylinder, and a retractable stop engaging said lever and arranged to be retracted when said handle locking means is released.

11. In valve reversing mechanism, the combination of a reversing cylinder, a piston therein, a reversing rod connected to said piston, a fluid actuated locking device

50 for said rod, valve mechanism controlling the supply and exhaust of motive fluid to and from the two ends of said cylinder and to and from said locking device, an actuating handle for the valve mechanism, a lock for said actuating handle, means for releasing said handle lock and therewith actuating said valve mechanism to admit motive fluid to the rod locking device to lock said rod and to the cylinder to actuate said rod, means for restoring said handle locking device after the handle has been moved and thereby partially restoring the valve mechanism to exhaust the rod locking device, and release said rod, and a retractable stop engaging said lever and arranged to be re-

tracted when said handle locking means is released.

12. In valve reversing mechanism, the combination of a reversing cylinder, a piston therein, a reversing rod connected to said piston, a fluid actuated locking device for said rod, valve mechanism controlling the supply and exhaust of motive fluid to and from the two ends of said cylinder and to and from said locking device, an actuating handle for the valve mechanism, a lock for said actuating handle, means for releasing said handle lock and therewith actuating said valve mechanism to admit motive fluid to the rod locking device to lock said rod and to the cylinder to actuate said rod, means for restoring said handle locking device after the handle has been moved and thereby partially restoring the valve mechanism to exhaust the rod locking device and release said rod, means actuated by the travel of said piston and permitting the handle locking device to be fully restored when the piston has traveled the desired distance and thereby further actuate the valve mechanism to release the cylinder, and a retractable stop engaging said lever and arranged to be retracted when said handle locking means is released.

13. In valve reversing mechanism, the combination of a reversing cylinder, a piston therein, a reversing rod connected to said piston, a fluid pressure actuated locking device for said rod, and valve mechanism controlling the supply and exhaust of motive fluid to and from the two ends of the cylinder and to and from said rod locking device and arranged to admit motive fluid to the locking device to lock said rod simultaneously with the admission of motive fluid to either end of said cylinder to actuate said rod, said valve mechanism comprising a seat, a rotary disk in operative relation thereto, a second rotary disk in operative relation to the first rotary disk, ports and passages in said disks and seat affording connection between a source of motive fluid and the two ends of said cylinder and said rod locking device and to the atmosphere, an actuating handle connected to one of said disks, and a handle locking device operatively connected to the other disk whereby said last named disk when actuated by the act of releasing said handle locking device admits pressure to said rod locking device to lock said rod.

14. In valve reversing mechanism, the combination of a reversing cylinder, a piston therein, a reversing rod connected to said piston, a fluid pressure actuated locking device for said rod, and valve mechanism controlling the supply and exhaust of motive fluid to and from the two ends of the cylinder and to and from said rod locking device and arranged to admit motive

fluid to the locking device to lock said rod simultaneously with the admission of motive fluid to either end of said cylinder to actuate said rod, said valve mechanism comprising a seat, a rotary disk in operative relation thereto, a second rotary disk in operative relation to the first rotary disk, ports and passages in said disks and seat affording connection between a source of motive fluid and the two ends of said cylinder and said rod locking device and to the atmosphere, an actuating handle connected to one of said disks, a handle locking device operatively connected to the other disk whereby said last named disk when actuated by the act of releasing said handle locking device admits pressure to said rod locking device to lock said rod, and means for restoring said handle locking means and thereby move said last named disk and exhaust said rod locking device to release said rod.

15. In valve reversing mechanism, the combination of a reversing cylinder, a piston therein, a reversing rod connected to said piston, a fluid pressure actuated locking device for said rod, and valve mechanism controlling the supply and exhaust of motive fluid to and from the two ends of the cylinder and to and from said rod locking device and arranged to admit motive fluid to the locking device to lock said rod simultaneously with the admission of motive fluid to either end of said cylinder

20 to actuate said rod, said valve mechanism comprising a seat, a rotary disk in operative relation thereto, a second rotary disk in operative relation to the first rotary disk, ports and passages in said disks and seat affording communication between a source of motive fluid and the two ends of said cylinder and said rod locking device and to the atmosphere, an actuating handle connected to one of said disks, a handle locking device operatively connected to the other disk whereby said last named disk

when actuated by the act of releasing said handle locking device admits pressure to said rod locking device, means for restoring said handle locking means and thereby move said last named disk and exhaust said rod locking device to release said rod, and means actuated by the travel of said piston arranged when the piston has traveled to the desired extent to permit further movement of the handle locking means and thereby further move the last named disk to exhaust said cylinder.

16. In valve reversing mechanism, the combination of a reversing cylinder, a piston therein, a reversing rod connected to said piston, a locking device for said rod, valve mechanism controlling the supply and exhaust of motive fluid to and from the two ends of said cylinder, an actuating handle for said valve mechanism, a lock for said actuating handle, and connections whereby the actuation of said handle lock to release said handle actuates said rod locking device to lock the reversing rod.

17. In valve reversing mechanism, the combination of a reversing cylinder, a piston therein, a reversing rod connected to said piston, a locking device for said rod, valve mechanism controlling the supply and exhaust of motive fluid to and from the two ends of said cylinder, an actuating handle for said valve mechanism, a lock for said actuating handle, connections whereby the actuation of said handle lock to release said handle actuates said rod locking device to lock the reversing rod, and means arranged upon the actuation of the valve mechanism to admit fluid to said cylinder and release said rod locking device.

In testimony whereof, I have hereunto set my hand.

JACOB RUSH SNYDER.
